UNITED STATES PATENT OFFICE.

GEORGE HENKEL, OF SPRINGFIELD, OHIO.

WATER CUT-OFF.

No. 857,171.

Specification of Letters Patent.

Patented June 18, 1907.

Application filed December 28, 1905. Serial No. 293,556.

To all whom it may concern:

Be it known that I, GEORGE HENKEL, a citizen of the United States, residing at Springfield, in the county of Clark and State of Ohio, have invented certain new and useful Improvements in Water Cut - Offs, of which the following is a specification, reference being had therein to the accompanying drawings.

10 This invention relates to water cut-offs, and is in the general nature of an improvement upon what is set forth in United States Letters Patent No. 470,489, granted to me March 8, 1892, for improvements in water cut-offs.

15 The general object of the invention is to provide an automatic device, for use more particularly in connection with the discharge spout of a roof, which will direct the first 20 flow of water from the roof during a rain, which flow is usually polluted with dirt and other washings from the roof and is therefore not desirable, to a suitable waste discharge; said device subsequently changing the direction 25 of the flow when the water has become clear and directing the same to a suitable storage receptacle, such as a cistern.

More specifically, my present invention has 30 for its object to provide a simple, compact, inexpensive and efficient mechanism by which these results may be obtained, and by which the amount of automatic waste discharge may be readily regulated, while the automatic feature may be rendered inoperative 35 at will, making the waste discharge permanent until the automatic action is again desired.

To these and other ends my present invention consists in certain novel features which I 40 will now proceed to describe, and will then particularly point out in the claims.

In the accompanying drawings, Figure 1 is a side elevation of a structure embodying my invention in one form; Fig. 2 is a plan view of 45 the same; Fig. 3 is a central vertical sectional view, taken on the line xx of Fig. 2 and looking in the direction of the arrows; Fig. 4 is a central vertical sectional view, taken on the line yy of Fig. 1 and looking in the direction 50 of the arrows; Fig. 5 is an enlarged detail sectional view, taken on the line zz of Fig. 4 and looking in the direction of the arrows; Fig. 6 is a diagrammatic view illustrating a different position of the parts from that shown in 55 the preceding figures; Fig. 7 is a similar view, showing the parts adjusted for permanent

discharge to waste; and Fig. 8 is a plan view of a portion of what is shown in Fig. 7.

In the said drawings, 1 indicates a suitable casing or housing, into which enters at the top a conduit 2, preferably in the form of a collar adapted to be connected to the discharge pipe of the roof of the building. The casing 1 is provided with or has connected to its lower portion a waste conduit 3 on one side of the central plane thereof and a storage conduit 4 on the opposite side, said conduits being preferably also in the form of collars adapted to receive pipes leading respectively to the waste discharge and to the cistern or other storage receptacle provided for water to be stored. Within the main housing 1 there is located a casing 5, preferably cylindrical in form, dividing the lower portion of the casing into two parts, communicating respectively with the waste outlet 3 and storage outlet 4. The casing 5 has at its top an inlet opening 6, while its lower portion is provided with an outlet opening 7, discharging toward the waste outlet or conduit 3. Within the casing 5 there is located a water wheel 8, mounted on a shaft 9, and preferably constructed in substantially the same manner as the water wheel of my prior Letters Patent hereinbefore referred to, the buckets being of such a character as to receive the water which enters through the opening 6 and retain the same so that the weight thereof will cause the wheel and its shaft to revolve, the water being discharged through the opening 7.

90 Between the discharge mouth of the entering conduit 2 and the top of the casing 5 there is located a deflector, consisting of a deflecting plate 10 having at its lateral margins upwardly extending flanges 11, by means of which the deflector is pivoted to the housing 1 through pivots 12 and 13. The pivot 12 is extended outside of the housing 1 and bent at an angle to form a detent arm 14, lying outside of the housing. A suitable weight is provided to move the deflecting plate, when free, to a position such as to cause it to discharge toward the storage outlet or conduit, as illustrated in Fig. 6. I prefer to attach this weight directly to one of the transverse margins of the deflecting plate, as shown at 15, thereby rendering the structure more compact and concealing and inclosing the weight within the housing. The deflecting plate 10 is further provided 105 with an aperture 16, through which a portion of the water which is discharged from the con-

duit 2 into the deflecting plate is permitted to pass to the inlet opening 6 of the inner casing 5 when the parts are in the position shown in Figs. 1 to 4, inclusive. In order to prevent too large a portion of the water from being thus diverted, I provide the deflector with an induction conduit 17, having a restricted receiving mouth 18. This conduit is preferably constructed in the manner shown, of a single sheet of metal bent to form two substantially parallel triangular sides, closed along one pair of their margins by the body of the metal itself, and along another pair of their margins by the deflecting plate 10, the opening 16 being located in this side, while the margins which are uppermost when the parts are in the position shown in Figs. 1 to 4 are separated so as to form a relatively narrow slot which forms the constricted receiving mouth 18, as shown more particularly in Fig. 2.

The shaft 9 projects through the housing 1 at one end and is there provided with a pinion 19, the same being preferably in the form of a disk secured to the projecting end of the shaft and having two pins 20 extending outward from its front face. These pins mesh with the teeth of a gear 21, mounted on a shaft 22, and any suitable provision may be made for causing the shaft and gear to rotate in unison, but I prefer the construction shown, in which the gear is loosely mounted on the shaft, the latter having an arm 23 mounted thereon, said arm having at its extremity a projection or finger 24, which engages an aperture 25 in the disk. The arm 23 is threaded to fit upon a threaded sleeve 23^a, splined or otherwise rigidly secured to the shaft 22 terminating in a stop or collar 23^b, against which the arm bears when the gear and arm rotate in unison. These parts are preferably supported in the manner shown, in which 26 indicates a base in the form of a bar secured to the outer face of the housing 1 on the front thereof and having an apertured lug 27 at its lower end. This bar has a bearing 28 for one end of the shaft 22 and a bearing 29 for one end of the shaft 9. A cover 30 incloses and protects this gearing, being connected to the base 26 by means of a lug or projection 31 at its lower end, fitting in the aperture of the lug 27 of the base, while the upper end of the cap or cover is provided with an apertured lug 32, through which passes a screw 33, which is threaded into the upper end of the base bar 26. The end of the shaft 22 which has its bearing at 28 is removable or separable from the bearing at that point, so that the said shaft, with the gear 21 and arm 23, is removable along with the cap or cover 30. The shaft 22 has a bearing in the cap or cover at 34, and extends outward beyond the cap or cover at that point.

65 The projecting extremity of the shaft 22

has attached to or formed thereon, preferably by bending the shaft at an angle, a trip arm 35. 36 indicates a trip lever, pivoted on the outer face of the casing between its ends, as indicated at 37. This trip lever has its extremities bent to extend outward at an angle to the body portion thereof, said extremities being indicated respectively by the numerals 38 and 39. It will be observed that the extremity or arm 38 is shorter than the extremity or arm 39, for the purposes hereinafter set forth.

In the ordinary or normal operation of the parts, they are first set to the position shown in Figs. 1 to 4, inclusive. In other words, the detent arm 14 is depressed and engaged by the shorter arm 38 of the trip lever 36, and in this position of the parts the longer arm 39 of said trip lever lies in the path of the tripping arm 35. This latter is shown in the drawings as being in a position such that it is just about to actuate the trip lever, but, when the apparatus is first set to operate, said trip arm will lie upon the other side of the arm 39. Assuming that a rain occurs, and that water from the roof enters the apparatus through the conduit 2, this first discharge of water, being undesirable, will be deflected by the plate 10 in such a way as to be discharged through the waste conduit 3. A small portion of this water will, however, enter through the restricted mouth 18 of the conduit 7, and will be discharged through the aperture 16, falling through the inlet opening 6 of the water wheel casing, and successively filling the buckets of the water wheel as the latter rotates. Excessive speed of the water wheel is prevented, however, by the restricted conduit which supplies the same. As the water wheel shaft 9 rotates along with the water wheel, the pinion 19 imparts a slow movement of rotation to the gear 21, and through this slow train to the shaft 22, which latter carries the tripping arm 35 slowly around until it comes into contact with the arm 39 of the trip lever. As the water wheel continues to rotate, the tripping arm moves the trip lever until the shorter arm 38 thereof releases the detent arm 14 of the deflector, whereupon the weight 15 swings the deflector over into the position shown in Fig. 6, thereby diverting the flow of water to the storage conduit 4. The relations of the parts are such that this shifting of the deflector does not occur until ample time has been allowed for the polluted water, which is first discharged, to be carried off through the waste outlet. It will also be noted that owing to the triangular shape of the conduit 7, with the parts in the position shown in Fig. 3, the mouth of the conduit is directed toward the incoming flow of water, so that a portion thereof is diverted to the water wheel, while the change of position of the deflector to that shown in Fig. 6 turns the closed portion of

said conduit toward the incoming water and the mouth away from it, so that no water enters said conduit, and the supply to the water wheel is cut off. After the discharge has 5 ceased, the apparatus may be reset in an obvious manner.

If the cistern or storage receptacle is full, or if, during a certain period, such as the winter season, it is not desired to store any of the 10 water, the automatic operation of the apparatus may readily be prevented, the deflector being located in a position such as to permanently discharge to waste. It is for this reason that the arms 38 and 39 of the trip lever 15 36 are made of different lengths. Upon referring to Figs. 7 and 8 it will be seen that the trip lever may be so turned as to engage its longer arm 39 with the detent arm 14, in which position of said lever the arm 38 is nearest to the trip arm 35. But said arm 38 is 20 too short to be engaged by said trip arm, which sweeps over it without touching it, so that the water wheel may revolve indefinitely without operating the trip arm and shifting 25 the deflector.

The screw threaded connection between the arm 23 and shaft 22 provides a simple and effective means for adjusting or regulating the quantity of the preliminary waste discharge. If the machine is set, as shown, with the arm 23 screwed up against the collar 23^b, then the shaft 22 rotates in unison with the gear 21 as soon as the water wheel starts, and the tripping arm begins at once to travel 35 around toward the trip lever. If a longer period of waste discharge is desired, all that is necessary is to move the arm 23 outward along the threaded sleeve 23^a away from the collar 23^b, and this may be readily effected by 40 simply turning the tripping arm 35 in a direction such as to cause the shaft 22 to rotate in its normal direction of rotation, but independently of the gear 21. This may be readily effected for the reason that the said gear is 45 loosely mounted on the shaft, and the frictional resistance of the water wheel and its shaft geared thereto is sufficient to hold the arm 23 against rotation, permitting the shaft 22 to turn therein. As the shaft 22 rotates 50 while the arm 23 is held against rotation, the said arm is moved outward along the sleeve 23^a, with which it is in threaded engagement, moving away from the collar 23^b, but maintaining its connection with the gear 21 by 55 reason of the engagement with the aperture 25 in said gear of the projection or finger 24. The arm 23 is thus moved outward or forward on its shaft a greater or less distance, according to the greater or less increase in 60 waste discharge desired. The apparatus then being set in the manner hereinbefore described, when the water wheel begins to rotate, the initial period of rotation in unison therewith of the gear 21 turns the arm 23 upon the 65 shaft 22, screwing it backward thereon until

the arm comes into contact with the collar 23^b, and during this period the tripping arm remains stationary. After the arm 23 engages the collar 23^b, the tripping arm rotates with the shaft 22 and finally actuates the trip lever to release the deflector. A more or less extended period of rotation of the water wheel is thus provided, during which the tripping arm is not traveling toward the trip lever, and the time intervening between the starting of the water wheel and the tripping of the deflector is thereby correspondingly increased. In case the shaft 22 should tend to turn with the gear 21 and arm 23 before the said arm is in contact with the collar 23^b, 70 such rotation can only continue until the tripping arm comes into contact with the trip lever, whereupon said tripping arm and its shaft will be held stationary by the resistance of the trip lever until the arm 23 engages the collar 23^b and the shaft 22 is positively turned to cause the tripping arm to overcome the resistance of the trip lever. In either case the trip lever will not be actuated until the predetermined time. It will thus be seen that provision is made for regulating the amount of 85 water discharged to waste, such regulation being readily effected.

It will be observed that the structure is compact, and that the water wheel and gear- 90 ing are so inclosed as to be effectually protected, the gearing being inclosed in a separate cover which is readily removable to give access to the same for inspection or repair. It will also be observed that the worm and 95 worm wheel employed in the structure shown in my former patent are dispensed with, and a form of gearing substituted therefor which is much less expensive in construction and simpler in operation, and which permits a 100 parallel arrangement of the shafts and pivotal axes of the moving parts, thereby further increasing the compactness of the structure.

I do not wish to be understood as limiting myself to the precise details of construction 105 hereinbefore described and shown in the accompanying drawings, as it is obvious that these details may be modified without departing from the principle of my invention.

Having thus fully described my invention, 110 what I claim as new and desire to secure by Letters Patent is:—

1. A water cut-off, comprising a casing, an inlet pipe communicating therewith, waste and cistern pipes leading therefrom, a deflector located beneath the inlet pipe and within the casing, locking means for releasably retaining the deflector in one position, a motor within the casing, means actuated by the motor for releasing the deflector, a shield 115 inclosing the motor and provided with an opening communicating with the waste pipe, the deflector and shield dividing the casing into two compartments, and means for supplying 120 motor power, substantially as described. 125 130

2. A water cut-off comprising a casing provided with an inlet and a plurality of outlet pipes, a motor located within the casing, a shield surrounding the motor and partially dividing the casing into two passages leading from the inlet to the two outlet pipes, respectively, the shield being provided with an opening leading to one of the outlet pipes, a deflector located beneath the inlet pipe, the 10 opposite ends of the deflector being adapted to engage the shield and coöperate therewith to completely divide the casing into two passages, and means for supplying the motor with power, substantially as described. 75
- 15 3. A water cut-off comprising a casing having an inlet pipe and a plurality of outlet pipes, a deflector for directing a stream from the inlet pipe to either of the outlet pipes, means for releasably locking the deflector at 20 one limit of its movement, a motor located within the casing, a shield surrounding the motor to inclose it within a chamber, means actuated by the motor for releasing the deflector, means for automatically reversing 25 the deflector, and means for supplying the interior of the shield-surrounded chamber with water, substantially as described. 80
- 30 4. In a water cut-off an entering conduit and branch discharge conduits connecting therewith, a deflector directing the flow into one or the other of said discharge conduits according to its position, a water wheel, a shield surrounding said water wheel to inclose the same in a chamber, and having an 35 inlet aperture therein, means actuated by said water wheel for controlling the position of said deflector, and means carried by said deflector for conducting to said aperture in said casing a portion of the flow, substantially as described. 85
- 40 5. In a water cut-off an entering conduit and branch conduits connecting therewith, a deflector directing the flow into one or the other of said discharge conduits according to 45 its position, a water wheel, a shield surrounding said water wheel and inclosing the same in a chamber, and having an inlet aperture therein, means actuated by said water wheel for controlling the position of said deflector, 50 and a conduit carried by said deflector and connecting said entering conduit with the aperture in said shield, substantially as described. 90
- 55 6. In a water cut-off, a main housing having an entering conduit at the top and two discharge conduits at the bottom, a pivoted deflector acting normally to direct the flow to one of said discharge conduits, a detent for holding the deflector in position to direct the 60 flow to the other discharge conduit, a water wheel casing located within the housing between said discharge conduits and having an inlet opening at its top and a discharge opening below, a water wheel located in said casing, and means operated by said water wheel 65 for actuating the detent to release the deflector, said deflector having an aperture which registers with the inlet opening of the water wheel casing when the deflector is engaged by the detent, said deflector also having a conduit communicating with its aperture and provided with a restricted receiving mouth which is presented to the flow when the deflector is held by the detent, substantially as described. 70
- 75 7. In a water cut-off of the character described, the combination with a water wheel and its casing having an inlet aperture, of a deflector comprising an apertured plate, and a triangular conduit mounted thereon and closed along one of its sides, the second side being closed, except for the aperture, by the deflecting plate, and the remaining side presenting a narrow receiving mouth, substantially as described. 80
- 80 8. In a water cut-off, a main conduit and two branch conduits, and a pivoted deflector normally directing the flow toward one of the discharge conduits, said deflector having a detent arm, a trip lever having an arm to engage said detent arm and hold the deflector in position to direct the flow to the other discharge conduit, a water wheel, and a tripping arm actuated from said water wheel, said trip lever having a second arm arranged in 90 the path of said tripping arm, said trip lever being reversible and both of its arms being adapted to engage the detent arm, while only one of said trip lever arms is adapted to be engaged by the tripping arm, substantially as described. 95
- 90 9. In a water cut-off, the combination, with a main conduit and branch conduits, and a pivoted deflector acting normally to direct the flow to one of said branch conduits, 100 of a detent for holding said deflector in position to direct the flow to the other branch conduit, a water wheel, mechanism operated by the water wheel for actuating the detent to release the deflector, and means for interrupting the operative connection between said detent and its actuating mechanism without releasing said deflector, substantially as described. 105
- 100 10. In a water cut-off of the character described, the combination, with a main housing containing a water wheel and deflector, and a water wheel shaft projecting through said housing and having a pinion, of a cap or cover detachably mounted on the exterior of the housing and a gear and tripping arm mounted in said cap or cover and removable therewith, substantially as described. 110
- 110 11. In a water cut-off an entering conduit and branch discharge conduits connecting therewith, a pivoted deflector acting to direct the flow into one of said discharge conduits when free, a detent holding said deflector in position to direct the flow to the other discharge conduit, a tripping arm for actuati- 115
- 120
- 125
- 130

ing said detent to release the deflector, a wa-
5 ter wheel, a shaft carrying said tripping arm,
and a threaded part on said shaft, a gear
loosely mounted on said shaft and actuated
by said water wheel, a threaded collar engag-
ing the threaded part of said shaft, and an
10 arm carried by said collar and engaging said
gear, whereby said gear moves independ-
ently of said shaft until said collar has
reached the inner limit of its movement, sub-
stantially as described.

12. In a water cut-off, an entering conduit
and branch discharge conduits communicat-
15 ing therewith, a pivoted deflector acting to
direct the flow into one of said discharge con-
duits when free, a detent for holding said de-
flector in position to direct the flow to the
other discharge conduit, a water wheel, a
20 tripping arm for actuating the detent to re-
lease the deflector, and gearing connecting
said water wheel and tripping arm and com-
prising two parts having threaded engage-
ment, rotating respectively in unison with
25 the water wheel and tripping arm and mov-
able by their threaded relations to an engage-
ment with each other whereby they rotate in
unison, substantially as described.

13. In a water cut-off of the character de-
scribed, the combination, with a shifting de-

flector and its detent, of a tripping arm and 30
shaft, a water wheel, a gear loosely mounted
on the shaft and driven from the water
wheel, and a connecting arm threaded on the
shaft and having a sliding engagement with
35 the gear to rotate in unison therewith, the
shaft having a stop against which the con-
necting arm is screwed by the rotation of the
gear, substantially as described.

14. In a water cut-off of the character de-
scribed, a shifting deflector and its detent, in 40
combination with a tripping arm and shaft, a
water wheel, a gear loosely mounted on the
shaft, driven from the water wheel, and pro-
vided with an aperture, and a connecting
45 arm threaded on the shaft and having a pro-
jection engaging the aperture of the gear,
whereby said connecting arm rotates in uni-
son with the gear and is movable longitudi-
nally of the shaft, said shaft having a stop
50 against which the connecting arm is screwed
by the rotation of the gear, substantially as
described.

In testimony whereof, I affix my signature
in presence of two witnesses.

GEORGE HENKEL.
